MOP PAIL

Willie O. Cleveland, Jr., Louisville, Ky.

Application March 17, 1944, Serial No. 526,997

2 Claims. (Cl. 280—44)

The present invention relates to new and useful improvements in mop pails used principally for cleaning floors and similar surfaces and the invention has for its primary object to provide rollers on the bottom of the pail to facilitate its movement over the floor and embodying means for moving the rollers into a retracted position so that the pail will then rest upon the floor and with the rollers out of contact with the floor, to prevent movement of the pail, when desired.

A further object of the invention is to provide simple and practical means for moving the rollers into and out of their retracted position and which at the same time is efficient and practical in operation, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which

Figure 1 is a fragmentary vertical sectional view of the bottom of a mop pail showing the rollers in position thereof,

Figure 2 is a top plan view, and

Figure 3 is a fragmentary sectional view taken substantially on a line 3—3 of Figure 1.

Referring now to the drawing in detail wherein for the purpose of illustration I have disclosed a preferred embodiment of the invention, the numeral 5 designates a mop pail generally which includes a bottom 6 positioned above the lower edge of the pail so that the sides of the pail extend downwardly below the bottom 6 as shown to advantage in Figure 1 of the drawing.

To the outside of the pail adjacent the lower edge thereof, are secured bracket members 7 arranged in pairs and between which a pin 8 extends for pivotally supporting the upper end of a mounting 9 for a roller 10 which is journaled on the lower end of the mounting.

The upper end of the mounting 9 is formed with an upwardly and outwardly extending arm 11 to which one end of a rod 12 is pivotally attached, the rod extending through an opening 13 formed in the side of the pail below the bottom 6.

An annular member 14 is secured to the under side of the bottom 6 and also has openings 15 in the sides thereof for freely receiving the rods 12 of the respective rollers.

A plate 16 is also secured to the under side of the bottom 6 from which a pin 17 extends downwardly having a flange 18 at its lower end, the

pin and flange providing a mounting for rotatably supporting a plate 19 thereon. A washer 20 is mounted on the pin above the plate 19 to space the latter from the plate 16.

The plate 19 is preferably square-shaped and adjacent each corner thereof the inner ends of the rods 12 are pivotally attached by means of eyes 21.

An eye 22 also extends downwardly from the plate 19 adjacent one side thereof and to which one end of a link 23 is loosely attached, the other end of the link being loosely connected to a crank 24 formed in a shaft 25 journaled in the ring member 14 as well as in the side of the pail 5, the shaft projecting outwardly therefrom and having a handle or treadle 26 secured to the outer end thereof.

In the operation of the device the mountings 9 for the rollers are normally maintained in a vertical position as shown by the full lines in Figure 1 of the drawing, whereby the rollers 10 will extend below the bottom edge of the pail so as to support the pail and permit the free travel of the pail along a floor or other surface. For this purpose the rollers 10 are provided with a swivel mounting to facilitate movement of the pail in any desired direction.

When it is desired to maintain the pail in a stationary position the handle or treadle 26 is moved downwardly whereby the plate 19 will be rotated through the medium of the link 23 and crank 24, thus causing an inward movement of the rods 12 which results in the raising of the roller 10 into the dotted line position shown in Figure 1. The pail will then rest upon the floor against free travel, and thus be maintained in a stationary position.

It is believed the details of construction, operation and advantages of the device will be readily understood from the foregoing without further detailed explanation.

Having thus described the invention, what I claim is:

1. An attachment for scrub pails comprising a plurality of roller mountings having rollers journaled thereon, means pivotally supporting the mountings to the side of the pail with the rollers extending below the lower edge of the pail to support the pail above a floor, an arm extending upwardly and outwardly from the upper end of each mounting, rods connected to the arms and extending toward the center of the pail, a rotatable member supported under the pail for movement about a vertical axis and to which the inner ends of the rods are attached, and means operable

from a position at the side of the pail for actuating said rotatable member in a manner to raise and lower said rollers.

2. An attachment for scrub pails comprising a plurality of roller mountings having rollers journaled thereon, means pivotally supporting the mountings to the side of the pail with the rollers extending below the lower edge of the pail to support the pail above a floor, an arm extending upwardly and outwardly from the upper end of each mounting, rods connected to the arms and extending toward the center of the pail, a rotat-

able member supported under the pail for movement about a vertical axis and to which the inner ends of the rods are attached, means operable from a position at the side of the pail for actuating said rotatable member in a manner to raise and lower said rollers, said means comprising a shaft journaled in the pail, a crank carried by the shaft, a link connecting the crank to the rotatable member, and a manual member for actuating the shaft.
